UNITED STATES PATENT OFFICE.

GEORGE W. BAKER, OF WILMINGTON, DELAWARE.

MACHINE FOR FINISHING THE TEETH OF CAST-METAL GEAR-WHEELS, &c.

No. 894,099.

Specification of Letters Patent.

Patented July 21, 1908.

Application filed December 28, 1907. Serial No. 408,439.

To all whom it may concern:

Be it known that I, GEORGE W. BAKER, a citizen of the United States, resident of Wilmington, in the county of Newcastle and

5 State of Delaware, have made a certain new and useful Invention in Machines for Finishing the Teeth of Cast-Metal Gear-Wheels, &c.; and I declare the following to be a full, clear, and exact description of the same, such 10 as will enable others skilled in the art to which it appertains to make and use the invention, reference being had to the accompanying drawings, and to letters or figures of reference marked thereon, which form a part 15 of this specification.

Figure 1 is a perspective view of the invention. Fig. 2 is a front-elevation of the same showing different location of the carrier for the dog and its supporting shaft. Fig. 3 is a 20 section on the line 3—3, Fig. 2, the lower part of the machine being in elevation. Fig. 4 is a section on the line 4—4, Fig. 2. Fig. 5 is a section on the line 5—5, Fig. 2, the shaft for supporting the gear wheel being removed. 25 Fig. 6 is a detail perspective view of the horizontally working slide and its link connections with the operating devices therefor. Fig. 7 is a side view of the attachment for bevel gears as applied, parts being broken 30 away. Fig. 8 is a detail side view of the attachment. Fig. 9 is a detail end view of the same with the mandrel removed. Fig. 10, is a detail sectional view on the line 10—10, Fig. 8, with the mandrel removed. Fig. 11 35 is a detail side view of the rack supporting attachment. Fig. 12 is a section on the line 12—12, Fig. 11.

The invention has relation to means for cleaning and finishing the teeth of cast metal 40 gear wheels, which are always defective and require much work thereupon in order to remove the hard scale with sand embedded therein and other irregularities. This work is now commonly done by hand in a laborious manner and it is the object of this invention to provide a complete, simple and practical machine, capable of operation by unskilled workmen, which will not only rapidly clean the teeth but will also shape the same 45 inside and out in an absolutely true manner, the result being gear wheels which appear to have been cut from the solid metal.

The machine is not confined in its use to 50 spur gears but operates equally well upon bevel and miter gears, racks, and toothed segments, besides a variety of other work

such as face grinding, surfacing of hard metals, etc.

With these objects in view the invention consists in the novel construction and combinations of parts as hereinafter set forth.

In the accompanying drawings, illustrating the invention, the letter *a*, designates the supporting frame, having a horizontal bed *b*, provided with a slideway *b'*, on which a slide *c*, is mounted and adapted to have movement of reciprocation. The slide has journalled in bearings at one end thereof the shaft or spindle *d*, having a reduced end portion *d'* upon which fits the grinding wheel *e*, adjusting nuts *e'*, and *e''*, being provided at each side of such wheel for purpose of lateral adjustment thereof, such nuts engaging right and left hand threads of the spindle.

The supporting frame *a*, has at one side 75 thereof a vertical slideway *f*, a head *f'*, engaging such slideway in a vertically reciprocatory manner and carrying a horizontal mandrel *f''*, designed to receive and support the gear wheel to be operated upon, marked 80 *x*. This head *f'*, is carried by a vertical screw rod *g*, having engagement with a threaded lug extension *f'''*, of the head, such rod having bearings in the horizontal bed of the machine at *g'*, and being supported by a 85 collar *h*, thereon resting upon a transverse bridge piece *h'*, spanning the bed and supported thereby. A crank handle *i*, at the upper end of the screw rod *g*, provides for rotation of the same to vertically adjust the 90 head *f'*, with mandrel *f''*, and the work thereupon.

In order to support gear wheels of some size and weight the outer end of the work supporting mandrel *f''*, is designed to rest in 95 a V-form head *j*, of a vertically adjustable support *j'*, the adjustment thereof being accomplished by hand after the gear wheel is set at the proper height by means of the screw rod and its crank handle aforesaid.

Horizontal reciprocation of the slide *c*, carrying the grinding wheel is accomplished by a hand wheel *k*, the shaft of which has journal bearings in the frame *a*, and carries a pinion *k'*, having engagement with a rack *e'*, 100 forming a part of the slide *c*.

l, is a driving pulley carried by a driving shaft *l'*, having bearings near the base of the frame at one end thereof. *l'', l'''*, are fast and loose pulleys upon said shaft. This shaft 110 carries a radial arm *m*, extending upward to approximately the height of the frame *a*, and

having a pivotal link connection m' , with the slide c .

In order to provide for even and constant rotation of the grinding wheel during its horizontal reciprocation an endless belt l^3 , passes around a pulley d^2 , of the shaft d , and is extended longitudinally of the machine around upper and lower guide pulleys or idlers n , and n' , carried at the upper end of the radial arm m , and thence downward around driving pulley l .

In the operation of the machine, a grinding or emery wheel is selected to correspond with the pitch of the spur gear to be ground, and placed on the reduced end portion of the grinding shaft or spindle d , when it is centered with respect to the mandrel f^2 , by suitable adjustment of the large compensating nut e' , and secured in such adjustment by tightening the outer nut e^2 . The spur gear to be ground is then placed on the mandrel f^2 , with collars o^4 , at front and back secured upon the mandrel by set screws. The gear is then raised to the proper height by rotation of the screw rod g , when the machine is started and the grinding wheel run through the teeth of the gear for the proper depth through operation of the hand wheel k .

The spur gear being operated upon is turned forward or toward the operator to present successive teeth to the action of the grinding wheel and in order to prevent backward turning of such wheel a dog p , is provided, said dog having a longitudinal adjustment in a carrier o' , pivoted at o^2 , to a shaft extension o^3 , of the head f' , such adjustment being secured by set screw p' . The inclination of this dog is varied by its pivotal adjustment upon the shaft o^3 , secured through set screw o^4 , to correspond with the size of the gear wheel being operated upon, and the dog has contact at its oblique or bent end-portion p^2 , with the rear side of one of the teeth of the gear being finished, a slight clearance shown at q , being allowed in order to compensate for slight imperfections in the dimensions of the teeth, which imperfection or difference, if any, will be corrected by action of the grinding wheel. As the work is turned towards the operator the dog will be automatically raised by the gear teeth, and will fall by gravity into position again.

r , represents a bevel gear attachment for the machine, comprising a body portion having a boxing r' , designed to be slipped upon the horizontal mandrel f^2 , and a pivotal arm r^2 having at one end thereof an arcuate slot r^3 , a bolt r^4 engaging such slot and the body portion of the attachment and acting to secure the pivotal arm in its adjustment, said pivotal arm having at the upper end thereof and in line therewith, a mandrel s . When the adjustment bolt r^4 is located in the middle of the arcuate slot r^3 , the mandrel s will have an angular relation to the horizontal of

forty five degrees, and through adjustment of the pivotal arm by means of its slot and bolt connection with the body of the attachment, the mandrel may be made to assume any angle from thirty to sixty degrees to the horizontal, or a larger angular range may be provided for.

Bevel or miter gears, the teeth of which have various angles may be placed upon the mandrel s , which is adjusted to correspond, when the teeth of such gears will be presented to the grinding wheel horizontally.

In Fig. 9 of the drawings is shown a table for use in grinding the teeth of racks. This table, marked t , is provided with lower extensions t' , cylindrically bored at t^2 , to fit upon the mandrel f^2 . The rack to be finished is placed upon this table, and through operation of the screw rod g , raised to the proper height, when the grinding wheel will be in position to act upon the teeth thereof.

Toothed segments may also have the teeth thereof sharpened in this machine, the procedure being similar to that for gear wheels.

Having described the invention, what I claim and desire to secure by Letters Patent is:

1. In a machine of the class described, a supporting frame, a slidable head carrying a horizontal mandrel adapted to support the work, a reciprocating grinding wheel, means for rotating the same, means for adjusting said slidable head and mandrel towards and away from the grinding wheel and an attachment device adapted to be supported upon said mandrel, and carrying an angularly disposed mandrel.

2. In a machine of the class described, a supporting frame, a slidable head carrying a horizontal mandrel adapted to support the work, a reciprocating grinding wheel, means for rotating the same, means for adjusting said slidable head and mandrel towards and away from the grinding wheel, and an attachment device for said mandrel carrying an angularly disposed mandrel and including means for changing the angle thereof.

3. In a machine of the class described, a supporting frame, a slidable head carrying a work - supporting mandrel, a horizontally working slide, a grinding wheel carried by said slide, means for reciprocating said slide and wheel, means for rotating said wheel including a driving pulley, a radial arm pivoted to the shaft thereof and having a pivotal link connection with said slide, upper and lower idler pulleys upon said radial arm, a pulley upon the shaft of said grinding wheel and an endless belt carried by said pulleys, and means for vertically adjusting said slideable head and mandrel.

4. In a machine of the class described, a supporting frame, a slidable head carrying a work - supporting mandrel, a horizontally working slide, a grinding wheel carried by

said slide, means for reciprocating said slide and wheel, means for rotating said wheel, and means for vertically adjusting said slideable head and mandrel including a vertical rod 5 having threaded engagement with the head and provided with a crank arm at its upper end.

5. In a machine of the class described, a supporting frame, a slideable head carrying a 10 work-supporting mandrel, a rotary reciprocating shaft, a removable grinding wheel carried thereby, said shaft being provided with means for lateral adjustment of said wheel thereupon to center the same with respect to 15 said mandrel, means for rotating said shaft and wheel, and means for adjusting said slideable head and mandrel towards and away from the grinding wheel.

6. In a machine of the class described, a 20 supporting frame, a slideable head carrying a work - supporting mandrel, a horizontally working slide, a rotary shaft carried thereby, a removable grinding wheel upon said shaft, said shaft being provided with right and left 25 hand threaded portions at opposite sides of the grinding wheel and adjustable nuts engaging said threaded portions whereby the grinding wheel may be centered with respect to the mandrel, means for reciprocating said

slide and wheel and for rotating said wheel, 30 and means for adjusting said slideable head and mandrel towards and away from the grinding wheel.

7. In a machine of the class described, a supporting frame, a slideable head carrying a 35 mandrel adapted to support the work, a horizontally working slide, a grinding wheel carried by said slide, means for reciprocating said slide and wheel including a rack and pinion device having an operating hand 40 wheel, means for rotating said wheel including a driving pulley, a radial arm pivoted to the shaft thereof and having a pivotal link connection with said slide, upper and lower idlers upon said radial arm, a pulley upon 45 the shaft of said grinding wheel and an endless belt carried by said pulleys and idlers, and means for vertically adjusting said slideable head and mandrel including a vertical rod having threaded engagement with the 50 head and provided with a crank arm at its upper end.

In testimony whereof I affix my signature, in presence of two witnesses.

GEORGE W. BAKER.
